UNITED STATES PATENT OFFICE.

HENRI RAYMOND GUYOT, OF PARIS, FRANCE, ASSIGNOR TO SOCIÉTÉ R. GUYOT & CIE., OF PARIS, FRANCE.

RADIATOR WITH REMOVABLE ELEMENTS.

Application filed November 22, 1922. Serial No. 602,582.

To all whom it may concern:

Be it known that I, HENRI RAYMOND GUYOT, a citizen of France, residing at 54 Avenue Jean Jaurès, in the city of Paris, France, have invented an Improved Radiator with Removable Elements, of which the following is a full, clear, and exact description.

This invention relates to a radiator for motor cars and other vehicles comprising removable elements or parts held within a frame so as to allow them to be replaced or isolated from the others in case of accident.

The elements of this radiator are provided upon an upper collector and a lower collector, with a joining device comprising a shell or box secured to a fixed plug provided with ports. When the radiator is operating normally, this joining device is ample, but when the element is to be isolated or separated, a shutter or closer is added to this device. The device thus combined forms the characteristic feature of the invention.

This invention will be hereinafter described by way of example with reference to the accompanying drawings in which:

Figure 1 shows in front view, part of a radiator with removable elements made according to this invention.

Figure 2 is a vertical cross section made through one of the removable elements.

Figure 3 is a vertical cross section of a connection without the closing device.

Figure 4 shows in vertical section one form of shutting or closing device as applied to the connection.

Figure 5 is a modified form of the shutting or closing device shown in Figure 4.

Figures 6 and 7 show other modified forms of this closing device.

Figure 8 shows in section a device provided with an insulating partition arranged inside the connection.

Figure 9 shows a closing shell ready to split the insulating partition.

Figure 10 shows the shell in position after the partition has been pierced.

Figure 11 shows in longitudinal section a modified form of closing shell made of two parts.

Figure 12 shows the point or tip of the shell engaged in the connection.

Figure 13 shows in section the body of the shell.

As shown in Figures 1 and 2 of these drawings, this radiator comprises removable elements A which can be of any system. This radiator comprises an upper header B and a lower header B¹ upon which are secured joining devices which allow the elements A to be replaced or isolated.

The joining devices are secured to the chambers a of the elements A, Figure 3, and each comprises a sleeve b, placed upon a hollow connection c opening into the headers B and B¹ of the radiator and secured to the headers.

When the elements are brought into position by causing them to move in the direction of the arrow, Figure 3, the cap d is screwed tightly until the two soft gaskets e are compressed.

The radiator header is directly connected with the chamber of the element through the holes or ports f of the connection c and the sleeve b, so that, during the normal running, the liquid to be cooled circulates without obstruction.

When it is intended to then isolate the element, it is only necessary to unscrew the cap d and to introduce into the hollow connection c a shell g, as shown in Figure 4.

The closing shell g is composed of two cylindrical pistons entering one another g¹ and g², within which a coil spring h is enclosed.

The external piston g¹ is provided with a rest or shoulder g³ for a gasket i, but this piston may be of any other form.

The screwing of the cap d causes, through the piston g² and the spring h, the piston g¹ to press the gasket i against the shoulder c¹ of the connection c thus producing a complete closure.

In order to re-establish the circulation in the element, it is only necessary to unscrew the cap d, to remove the whole of the shell g, and place the cap again in position.

In Figure 5, the shell in question is formed of a single sliding piston g held by a spring h pressing against a washer j mounted upon

a central stem k secured by a nut l . The piston carries any suitable form of gasket i resting upon the seat c^1 of the connection c .

The shell being in position, a pressure is exerted, when tightening the cap d , upon the central stem or rod k which acts upon the spring h and upon the piston g , thus obtaining an elastic pressure and a complete closure.

- 10 In Figure 6, the shell is composed of a stopper made of india-rubber or any other extensible substance g through which passes a screw-stem or bolt m provided, at one end, with a head m^1 and at the other end with any suitable nut m^2 . When tightening this nut, a pressure is exerted upon the two ends of the stopper which swells and then shuts off the port or holes f .

Figure 7 of the drawings shows a modified form in which the shell g is pressed against a gasket i by means of a screw n screwed into the hollow connection c .

In the modified form shown in Figures 8 to 10, the inner portion of the connection c is provided with a shoulder c^1 near the inlet portion upon which is applied a thin insulating partition x which can be of any suitable material provided it can be easily pierced.

30 In case such a partition is used, the shell g is provided with a point g^4 adapted to pierce this partition. The perforated partition then surrounds the body of the shell as shown in Figure 10 of the drawings, after the screw-plug y has driven this shell home so that its soft fitting i presses against the obturating cone c^2 . The use of this partition avoids waste of water when an element is being isolated.

40 In the modified form shown in Figures 11, 12 and 13, the shell is made of two parts, so that its head only may be used when it is desired to replace a damaged element by a spare one without emptying the radiator.

45 To this purpose, the body of the shell and the point or tip thereof are made removable so as to allow a quick separation of these two parts.

In this case, the body g of the shell, is provided at the front, in order that it can be separated from its point or tip g^5 , with a threaded cylindrical part g^6 forming a stud which is screwed into a tapped part g^7 in the back of the shell point.

55 This conical point g^5 is provided with a shoulder g^8 and a central threaded stem g^9 .

A soft washer i made of india-rubber for instance is placed upon the part g^5 and rests upon the shoulder g^8 ; it is pressed by a metallic washer g^{10} and a nut g^{11} against the shoulder g^8 so as to produce its expansion.

The nut g^{11} has a conical point g^4 which acts as a punch in order to pierce the insulating partition x , as above stated.

65 The insulation of a damaged element is

performed quite simply in the following manner: 1st. The cap is unscrewed; 2nd. The insulating partition x is pierced by means of the point g^4 , which prevents the water of the radiator from flowing out; 3rd. The closing shell g is pushed home until its soft part i comes in contact with the cone c^2 .

70 After the cap d has been again screwed so as to cause the shell to firmly bear against the cone c^2 , the radiator may then be operated again.

If during the journey, it is desired to replace a damaged element by a spare one, without emptying the radiator, it is only necessary after having effected the insulation, as above indicated, to unscrew the tightening nut d^1 , which enables the substitution of an element for another without any waste of water.

80 The new element being kept in position by the nut d^1 , it is then put again in circuit with the collectors of the radiator by withdrawing the shell until the soft part of the head comes in contact with the inlet part of the connection c , then the body of 90 the shell is separated from the head.

Finally, after the cap d has been placed again in position, the radiator is ready to operate with all its elements.

95 The head of the shell which closes the connection c can be removed and replaced by a spare insulating partition x .

100 The forms, details, accessories, materials and sizes of this radiator can of course vary without in any way departing from the principle of this invention.

What I claim is:—

1. In a radiator having removable elements, a tubular member connecting the header of the radiator with an element 105 thereof, a cylindrical member adapted to be inserted in the tubular member for closing the communication between a header and an element, said cylindrical member comprising two telescoping and spring-pressed sections, and means for telescoping the said sections.

2. In a radiator having removable elements, a tubular member connecting an element with a header of the radiator, a member adapted to be inserted in the tubular member for closing the communication between the element and header, said closure member comprising two cylindrical shells 115 each having a closed end and telescoping one in the other, and a spring in the shells and engaging the closed ends thereof, and means for telescoping the said shells.

3. In a radiator having removable elements, a tubular member connecting an element of the radiator with a header thereof, a breakable partition at one end of the member, a cylindrical member adapted to be inserted in the tubular member for closing the communication between the element 125 130

and header, said cylindrical member having a pointed end, whereby the partition will be broken and caused to surround said member as it is inserted in the tubular member.

4. In a radiator having removable elements, a tubular member for connecting an element of the radiator with a header thereof, a member adapted to be inserted in the tubular member for closing the communication between the header and an element, said closure member comprising two telescoping and spring-pressed shells having a removable head provided with a gasket surrounding the same, and means for telescoping said shells.

5. In a radiator having removable elements, a tubular member for connecting an

element of the radiator with the header thereof, said member having a beveled surface at one end and provided at its other end with a breakable partition a member adapted to be inserted in the tubular member to close the communication between the element and header, said closure member comprising two telescoping and spring-pressed shells and a head detachably secured to one of the shells and having a gasket surrounding the same and provided with a pointed end, and means for telescoping the said shells.

The foregoing specification of my "improved radiator with removable elements" signed by me this 7th day of November 1922.

HENRI RAYMOND GUYOT.
